UNITED STATES PATENT OFFICE.

MARVIN SMITH, OF LAWRENCEVILLE, VIRGINIA, ASSIGNOR TO L. P. SMITH AND NELLIE C. SMITH, BOTH OF ROANOKE, VIRGINIA.

SIGNAL FOR MOTOR VEHICLES.

Application filed August 13, 1920, Serial No. 403,252. Renewed February 24, 1925.

It is important, in order to get the most efficient service out of an automobile or motor vehicle and to maintain it in good running condition, to keep up the supply of lubrication or other material necessary for the proper working of the vehicle parts or members. This should be renewed or replenished periodically, having reference to the consumption or waste that takes place both from the actual movements of the parts concerned and from evaporation. Therefore, the two factors must be considered of loss or change of volume by mileage actually run and from mere lapse of time and the best result cannot be secured unless both factors are reckoned with. The object of my invention, accordingly, is to provide means which automatically will call attention to the requirements of the vehicle in respect of those things that are consumed or wasted so that in good time the user will be admonished to attend thereto. Other objects and advantages of my invention will appear or be understood by those skilled in the art when the means or devices I employ are understood from the hereinafter given description. My invention consists in the mechanism described by or included within the scope of the appended claims.

In the accompanying drawings:

Fig. 1 is a front view of a known type of speedometer embodying my invention;

Fig. 2 is a view on a larger scale in vertical section showing the signal operating mechanism;

Fig. 3 is a detail view of the change gear device;

Fig. 4 is a front elevation of another form of my invention;

Fig. 5 is a section on the line 5—5 of Fig. 4;

Fig. 6 is a detail view of a clutch device that may be used in the transmitting mechanism of the signal device.

Briefly described, my invention comprises in the embodiments shown in the drawings, a legend carrying or exhibiting member preferably of a type which is visual that is caused to display the legend either when a predetermined mileage is run or a predetermined period of time has elapsed, the display in the former case being effected by or under the control of the odometer or a motor driven device, and in the latter case being effected by or under the control of a time piece preferably mounted in the same speedometer casing. Thus, if for any reason the car should

not be run a mileage calling for the renewal or replenishment of, say, lubricating oil, notwithstanding a sufficient period of time had elapsed requiring such renewal or replenishment the signal or warning would nevertheless be displayed thru the action of the time piece; and if either of the signal display controlling devices should for any reason not affecting the other fail to cause the display of the signal the other will cause its display.

Referring to Figs. 1, 2, and 3 of the drawings, 10, designates a speedometer of known construction having a speed indicator, 11, a trip odometer, 12, a season odometer, 13, and a clock, 14. At some convenient place in the speedometer dial is a display hole, 15, to and from which is movable a plate or tablet, 16, said tablet being mounted on a pivot, 17, and acted upon by a spring, 18, which tends to swing it from the hole, 15, to display the warning signal, which may be a word or legend printed or painted and visible thru the hole, 15. The tablet or shutter, 16, is latched in position to conceal the signal or warning by a trip arm, 19, that engages a tooth, 20, on the side of the tablet. The tail of the trip, 19, is in the path of a rotating tooth, 21, on a shaft, 22, that carries a pinion, 23, which, by change gears, 24, receives motion from both the odometer, 13, and the clock, 14. The change gear includes a shaft, 25, loose upon which are two worm wheels, 26 and 27, respectively, the former being engaged by a worm 28, on a shaft, 29, connected by suitable gears, 30, with the odometer, and the latter being engaged by a worm, 31, on a shaft, 32, connected by gears, 33, with the clock train. The worm gears, 26 and 27, may be clutched to the shaft, 25, by some suitable clutch device that permits the rotation of the shaft independently of the gears, such, for example, as the ball clutch shown in Fig. 6. Thus, tho both odometer and clock are geared to the shaft, 25, either may rotate the shaft independently of the other and hence, if, for example, the odometer should not have registered the mileage at which the signal should be displayed altho, in point of fact, the period of time had expired when the signal should be displayed, the clock will cause its display and during the period of inaction of the odometer, by reason of the non-running of the car, which would be responsible for the mileage shortage, the clock would run the shaft, 25. I provide the change gear, 24,

because at different seasons of the year or under different climatic conditions the mileage or periods of time when the material should be replenished vary. As no specific claim is made herein to the change gear construction which, therefore, forms no part of the present invention, it is unnecessary to give more than enough description of what is shown in the drawings to make the construction and operation of such change gear understood. The change gears, 24, include two trains which are of graduated diameter as clearly shown in Fig. 2, one of which trains is stationarily mounted with reference to the other and such other is carried by a frame clearly shown in Fig. 3 as slidably mounted upon parallel rods so that by shifting said frame laterally along the rods, one set of gears of the two trains or another set will be meshed, and thus the timing changed. The pinion, 23, is elongated because it must be kept in mesh with all of the gears of the shiftable train, no matter to what position laterally the shiftable train is moved. A suitable slide, 34, and cooperating scale are provided on the exterior of the odometer for convenient manipulation of the change gear, such slide, 34, being as clearly shown in Fig. 2 connected by a link and lever with the slideable frame which carries the shiftable train of gears.

Referring to Figs. 4 and 5, the dial of the speedometer, 10, has an arcuate slot, 35, at the top and back of the dial is a flat-sided ring, 36, supported so that it may rotate concentric with the center of the speedometer, said ring having a diameter that results in the display on its flat outer face at the slot, 35, and thus the exhibition at such slot of any one of a plurality of legends on such face that call attention to something to be done in relation to the vehicle at certain periods. The ring, 36, has on its back a crown gear, 37, with which meshes a pinion, 38, in a train of gears, 39, that receives motion from the odometer driving shaft, 40, and hence not from the odometer, 13, altho the pinion, 38, thus effects the display of the legends of the ring, 36, on a mileage basis. A pinion, 41, also meshes with crown gear, 37, such pinion being in a train, 42, of gears deriving motion from the clock, 14, the pinions, 38 and 41, having a clutch connection with their respective shafts, such as that shown in Fig. 6 and which allows the ring, 36, to be driven either from the odometer or the clock. The clutch connection between the pinions, 38 and 41, and the ring, 36, allows the latter to be rotated independently of said pinions and hence it may be turned at will to adjust the time of display of the signals at the opening, 35, a suitable turning knob, 43, on the exterior of the speedometer being provided that is suitably geared to said ring, 36, for turning the same. The shutter form device, 16,

of Fig. 1, is reset, when tripped, by a rod, 44, that extends to the exterior of the odometer.

I show in Fig. 1 a signal, 45, controlled by the clock alone, but as that forms the subject of another application for patent, I do not claim it herein.

What I claim is:

1. An indicator for motor vehicles having means for calling attention to some matter in relation to the vehicle, comprising a signal member movable to and from display position, and a plurality of control mechanisms for said member, each of which acts independently of another whereby if one does not cause the display of said member another will.

2. An indicator for motor vehicles having means for calling attention to some matter in relation to the vehicle, comprising a signal member movable to and from display position, and a plurality of control mechanisms for said member, each of which acts independently of another whereby if one does not cause the display of said member another will, one of said control mechanisms being a time piece and the other a mileage device.

3. An indicator for motor vehicles having means for calling attention to some matter in relation to the vehicle, comprising a signal member movable to and from display position, and a plurality of control mechanisms for said member, each of which acts independently of another whereby if one does not cause the display of said member another will, and an additional signal member under the control of one of said control mechanisms only.

4. An indicator for motor vehicles comprising a device for calling attention to some matter in relation to the vehicle and a plurality of dissimilar control mechanisms for said device, each of which acts independently of another, whereby if one does not render said device active, another will.

5. An indicator for motor vehicles comprising a device for calling attention to some matter in relation to the vehicle and a plurality of control mechanisms for said device, one of said control mechanisms being a time piece and the other a mileage device and each acting independently of the other whereby if one does not render the device active, another will.

6. An indicator for motor vehicles comprising a movable member calling attention to some matter in relation to the vehicle requiring attention, means operated on a mileage basis, a time piece, and an operative connection from said means and time piece to said member to control the movement of such member, the control by the timepiece being independent of the control by the mileage basis means, whereby if one is not active upon said device, the other will be.

7. An indicator for motor vehicles com-

- prising a movable member calling attention to some matter in relation to the vehicle requiring attention, means operated on a mileage basis, a time piece, and an operative connection from said means and time piece to said member to control the movement of such member, said operative connection permitting action of one independently of the other and comprising a clutch device for each.
- 10 8. An indicator for motor vehicles comprising a movable member calling attention to some matter in relation to the vehicle requiring attention, means operated on a mileage basis, a time piece, and an operative connection from said means and time piece to said member to control the movement of such member, said operative connection including change gearing.
9. An indicator for motor vehicles comprising matter to be displayed periodically and a moving member shiftable to and from
- 15 a position to effect the display or non-display of such matter, means operated on a mileage basis that effects the movement of said member, and means operated on a time basis 25 that independently effects the movement of such member.
10. An indicator for motor vehicles comprising matter to be displayed periodically and a moving member shiftable to and from 30 a position to effect the display or non-display of such matter, means operated on a mileage basis that effects the movement of said member, means operated on a time basis that independently effects the movement of said 35 member, and means for varying the lengths of the periods of time for causing movement of said member.

In testimony whereof I hereunto affix my signature.

MARVIN SMITHEY.
